UNITED STATES PATENT OFFICE.

FREDERICK WILL, SR., AND HUGO BECKER, OF ROCHESTER, NEW YORK, ASSIGNEES TO
SILL STOVE WORKS, OF ROCHESTER, NEW YORK, A CORPORATION OF NEW YORK.

COMBINATION COAL AND GAS STOVE.

1,169,219.

Specification of Letters Patent.

Patented Jan. 25, 1916.

Application filed December 28, 1911. Serial No. 668,213.

To all whom it may concern:

Be it known that we, FREDERICK WILL, Sr., and HUGO BECKER, both of Rochester, in the county of Monroe and State of New York, have invented certain new and useful Improvements in Combination Coal and Gas Stoves; and we do hereby declare the following to be a full, clear, and exact description of the same, reference being had 10 to the accompanying drawings, forming a part of this specification, and to the reference-numerals marked thereon.

The present invention relates to stoves, of the particular type adapted for burning either coal or gas having independent ovens arranged to be heated by either kind of fuel, and it has for its object to provide a stove embodying these features in a unitary structure, which can be readily manufactured and is extremely efficient in operation.

A further object of the invention is to provide a stove embodying these elements in an integral unit, possessing a neat appearance and a compact arrangement of parts.

Another object is to provide a structure such that when coal is being burned, the gas heated oven will serve as a warming oven, and vice versa.

Still another object is an arrangement whereby no dampers are required in the gas burning section, the products of combustion being satisfactorily carried off from the gas burners to the main flue, and when coal is being burned, the draft is not interfered with by the connection from the gas burning section.

To these and other ends the invention consists in certain improvements and combinations of parts, all as will be hereinafter more fully described, the novel features being pointed out in the claim at the end of the specification.

In the drawings: Figure 1 is a front elevation of a stove, constructed in accordance with a preferred embodiment of our invention; Fig. 2 is a plan view of the same; Fig. 3 is a transverse vertical section on the line $\alpha-\alpha$ of Fig. 2, and Fig. 4 is a longitudinal, vertical sectional view of one end of the stove.

Similar reference numerals throughout the several figures indicate the same parts.

In the embodiment of the invention herein disclosed wherein we have shown a preferred form and arrangement of parts, there is afforded at one end of the stove a coal burning section embodying an oven 1, adapted to be closed by the oven door 2, 3 being the usual fire door adjacent to the oven door: Arranged at the opposite end of the stove, adjacent to the coal burning section is a gas burning section including the oven 4, the latter being provided with the oven door 5. The gas burning section and the coal burning section are both supported on the base frame 6 mounted on suitable legs 7. The base frame extends around the entire body of the stove, as shown, affording an extremely neat and efficient arrangement. The gas and coal burning sections of the stove are separated by a single partition for a purpose that will appear presently, and to this end a wall is provided between the sections embodying a vertically disposed portion 8 extending from the bottom of the stove body to a point somewhat below the top thereof, and an angularly disposed portion 9 extending from the top of the vertically disposed portion to the top of the stove, as shown clearly in Fig. 4. The oven 4 is provided with a removable top embodying an upper wall 9^a and lower wall 10, a space 11 being afforded between the same. The upper wall 9^a has an opening 12 at its rear end, whereas the lower wall 10 is provided with the opening 13 at its front end, thus affording a passage from the oven to the flue for any products of combustion or gases that may be collected within the oven, the rear wall of the latter being provided with the openings 14 leading to the heated space surrounding the oven. Openings 15 are afforded in the side walls of the oven, said side walls being also provided with suitable lugs 16 to afford supports for racks or shelves to be placed within the oven.

When it is desired to use a broiler, the top of the oven is removed and may be supported on either of the sets of lugs 16 until the oven is desired for use again, and this construction enables the broiler and oven chambers to be adjusted to the desired size, while both can be operated at the same time, if desirable. Burners 17 are provided beneath the oven, of which two are illustrated in the drawings and burners 18 are arranged

immediately above the oven. At the upper part of the gas burning section are the burners 19 for heating the top 20 said burners being arranged within a chamber formed by the horizontal wall 19^a, which separates the burners at the top of the gas burning section from the oven. Gas is supplied to the burners 18 by means of pipes which lead in from a side wall of the burner chamber at points above the wall 19^a. The latter, which covers the gas burning section, extends as shown beyond the vertically disposed portion 8 and to the upper edge of the angularly disposed portion 9 of the separating wall between the sections, and the coal burning section is provided with a top 21 which extends substantially to the upper edge of said angularly disposed portion 9, there forming a joint with the top 20. By this arrangement of the wall which separates the gas and coal burning sections in the stove, sufficient radiation of heat is afforded from one section to the other to constitute a warming oven of either oven when the section containing the other oven is being operated; that is to say, when gas is burned in the gas burning section the oven 1 may be used as a warming oven and vice versa. By providing the angularly disposed portion 9, the upper burners 19 can be disposed in closer relation to the coal burning section of the stove, economizing the accessible space and affording a more compact and neater structure, while also adding to the utility of the stove. Furthermore, when the coal burning section is in operation, the angularly disposed portion 9 is directly exposed to the products of combustion from the coal burning section and is an efficient radiator of heat, thus enabling articles on the top of the gas burning section to be kept warm from the heat of the coal burning section and tending to warm the air in the gas burning section sufficient to overcome any tendency to check the coal

fire by admission of cold air to the main flue from the gas burning section.

The coal burning section is provided with the main flue 22, to which a pipe 23 leads from the back of the gas burning section. A free discharge is afforded through the pipe 23 at all times, no damper or cut off being afforded, for the reason that when the coal burning section is in operation, the air in the gas burning section is heated sufficiently by the radiating currents to overcome any harmful results that might accrue from the passage of cold air to the main flue 22 from the pipe 23.

The provision of such a construction whereby we are enabled to connect the gas burning section with the flue of the coal burning section without the use of any damper therebetween, we consider an important feature of our invention, because it is highly undesirable to have any controlling damper in the pipe which leads from the gas burning section. If there is such a damper, it is not unlikely, and often happens, that a person will use the gas burning section when the damper is closed, and this may result in an explosion, or a discharge of dangerous gases into the room.

We claim as our invention:

In a stove, the combination with a coal burning section, of a gas burning section, a wall separating said sections, the gas burning section including an oven, a burner arranged above the oven, and a removable top for the oven comprising an upper wall having an opening in its rear end, and a lower wall having an opening at its front end, the upper and lower walls affording a space therebetween.

FREDERICK WILL, SR.
HUGO BECKER.
